UNITED STATES PATENT OFFICE.

GEORGE E. SILVERNAIL, OF GALVESTON, TEXAS.

SURF-TOBOGGAN.

1,262,989.

Specification of Letters Patent. Patented Apr. 16, 1918.

Application filed June 20, 1917. Serial No. 175,783.

To all whom it may concern:

Be it known that I, GEORGE E. SILVERNAIL, a citizen of the United States, residing at Galveston, in the county of Galveston 5 and State of Texas, have invented certain new and useful Improvements in Surf-Toboggans, of which the following is a specification.

This invention relates to surf toboggans 10 of the type that are inflated with air for use by bathers and others disporting in the surf.

The casing of the toboggan is made of canvas or other suitable fabric, and it is 15 an object of the invention so to form the casing for reception of inflating tubes or the like that it will be devoid of interior partitions. A casing so formed may be turned inside out after use, so that the in- 20 side may be dried thoroughly, and also in order that ripped seams may be repaired easily. In repairing the interior stitching of a toboggan having interior sewed in partitions, it is necessary to rip the outer 25 casing to have access to the interior for the purpose of repair, as it cannot be turned inside out, but this necessity is avoided in the casing formed in accordance with this invention.

30 The invention also contemplates a novel disposition of the lacing and flaps of the casing, and of the coverings of the inflating-members placed in the casing.

When read in connection with the description herein, the details of construction and arrangement of parts contemplated by the invention will be apparent from the accompanying drawing, forming part hereof, wherein an embodiment of the invention is 40 disclosed, for purposes of illustration.

While the disclosures herein now are considered to exemplify a preferable embodiment of the invention, it is to be understood that it is not the intention to be limited 45 necessarily thereto in interpretation of the claims, as alterations and adaptations within the limits of the claims can be made without departing from the nature and spirit of the invention.

50 Like reference-characters refer to corresponding parts in the views of the drawing, of which—

Figure 1 is an end view with the flaps laced closed;

55 Fig. 2 is an end view with the outer flap open.

Fig. 3 is an end view with both flaps open; Fig. 4 is a top view, the outer casing being partially broken away;

Fig. 5 is a side view;

Fig. 6 is a view of the cover of one of the inflating-casings; and

Fig. 7 is a view of one of the inflating casings.

Having more particular reference to the drawings, 8 designates an air-tight inflating casing or tube, which is provided at one end with a screw-threaded inflating and deflating nipple and valve 9 of usual form. The inflating-casing is disposed within a 70 cover 10 of canvas or other suitable fabric, and it has at one end flaps 11 and 12 formed with eyelets 13 through which lacing 14 is passed to hold the flaps in position to close the cover and retain the inflating casing 75 therein. The cover also has a gromet 15 providing an opening in the wall at the same end as the flaps to accommodate the nipple 9 and to permit it to project outside of the cover where it is accessible for the 80 purpose of inflating and deflating the inflating-casing.

Each of the covers is formed of a single strip of fabric 16 constituting the flap 11 at one end and extending across that end, 85 along the bottom, across the other end, and back to the flap end, where its terminal portion constitutes the other flap 12, and the lateral margins of the strip have stitched to them fabric strips 17 forming 90 the side walls of the cover.

A sufficient number of these inflating casings and covers to fill it when inflated are placed within an outer casing 18. The outer casing is formed of side fabric walls 19 95 stitched to the lateral margins of a length of fabric material 20, which extends as the top of the casing from the rear end to and around the front end, and then as the bottom back to the rear end, and upwardly as 100 the rear wall. The rear ends of the length of material 20 are not stitched together, but they are left free to provide an opening 21 for reception and removal of the inflating casings and covers, so that the end wall at 105 its upper edge constitutes an inner flap 22. The end portions of the material are formed with eyelets 23 to receive lacing 24 to hold the flap 22 closed. The rear end wall of the casing, below the part thereof that is termed 110 the flap 22, is formed with a series of gromets 23^a providing openings regularly

spaced of a number equal to the number of inflating casings used, to accommodate the nipples 9 and to permit them to extend outside of the end wall where they are accessible 5 for the purpose of inflation and deflation.

In order to afford a covering for the nipples, an outer flap 24^a is sewed to the rear portion of the under side of the casing and extends upwardly outside of the end wall of 10 flap 22, and in its upper marginal portion it is provided with eyelets 25, which register with the eyelets 23. The outer flap is laced closed by the lacing 24, which is passed through both the eyelets 23 and 25.

15 The outer casing is curved upwardly at its front or bow end to facilitate its taking and riding over the surf when in use underneath a bather, and the inflating-casing covers are correspondingly shaped, so that when the inflating-casings are distended the outer casing 20 will be filled and distended to the shape intended.

When the outer casing is to be filled, a sufficient number of cover-contained inflating-casings are placed therein through the opening 21 and the nipples passed through the gromets 23^a. The inflating-casings then 25 are inflated by means of a suitable air-pump and the outer casing thereby distended to shape, and then the outer casing flaps are laced together and the article is ready for use.

In the event that it is necessary to repair 30 one of the inflating casings or its cover, it is not necessary to withdraw all of them and render the article unavailable for use. Only the one to be repaired is deflated and with-

drawn, and an extra inflating-casing and cover is substituted. Thus it is not necessary to put the toboggan out of commission 40 while repairs are under way.

Having thus described my invention, what I claim as new, and desire to secure by Letters Patent, is—

1. An article of the kind described comprising an outer casing having an opening, an inner flap arranged to close said opening and having therein openings for accommodation of inflation-nipples, and an outer flap arranged to cover said latter openings, there being registering eyelets in the casing, inner flap and outer flap whereby both of said flaps may be closed by the same lacing. 45

2. An article of the kind described comprising an outer casing inclosing a single chamber and having a single opening leading to said chamber, an inner flap arranged to close said opening and having openings therein for accommodation of inflation nipples, a plurality of covers in said outer casing each containing an inflating-casing having a nipple extending through the cover and through said flap, and an outer flap on said outer casing arranged to cover said nipples, there being registering eyelets in the outer casing, inner flap and outer flap whereby both of said flaps may be closed by the same lacing. 55 60 65

In witness whereof, I affix my signature.

GEORGE E. SILVERNAIL.
